TO JOSIAH ANSTICE & CO. INC., OF ROCHESTER, NEW YORK

BURNISHING MACHINE

Application filed January 21, 1931. Serial No. 510,309.

This invention relates to improvements in burnishing machines the particular conception embodying the invention being more particularly designed and intended as a burnishing machine for silver tableware.

The primary object of the invention is the provision of an improved silver burnishing machine.

A further object of the invention is the provision of an improved means or method of removing silver from the machine.

A still further object of the invention is the provision of a rotary tumbling barrel for the machine of a novel construction having novel means for starting and stopping the rotation of the same.

A still further object of the invention is the provision of an improved trap for the outlet of the machine tub.

Another and further object of the invention is the provision of an improved drive for the machine including a novel form of clutch.

Other specific objects and specific improvements incorporated in the machine forming this invention will appear from the following description and accompanying drawings.

In the drawings,

Figure 1 is a perspective view of a machine built in accordance with the present invention;

Figure 2 is a vertical sectional view, the machine drive not being shown;

Figure 3 is an end view, the tub and trap being shown in vertical section;

Figure 4 is an end view of the housing enclosing the machine drive;

Figure 5 is a vertical sectional view taken on the line 5-5 of Figure 4 looking in the direction indicated by arrow;

Figure 6 is a top plan view of the outlet trap;

Figure 7 is a side view of the outlet trap;

Figure 8 is another side view of the outlet trap;

Figure 9 is a detail section through a modified form of latch;

Figure 10 is an elevation of the same;

Figure 11 is a perspective view of one of the burnishing members;

Figure 12 is a longitudinal section through

a modified form of burnishing and rinsing machine showing the tumbling barrel with a foraminous lining;

Figure 13 is a detail sectional view showing the upper edges of the lining beveled to facilitate the insertion of the lining within the tumbling barrel;

Figure 14 is a perspective view of a portion of a tumbling barrel showing the manner of securing a wooden lining therein;

Figure 15 is a detail longitudinal section showing the manner of securing the heads within the barrel;

Figure 16 is a transverse section through a tumbling barrel provided with a composition lining;

Figure 17 is a detail view showing the bolts for securing the same in position in dotted lines;

Figure 18 is an elevation of the divider in connection with the tumbling barrel; and

Figure 19 is an end view of the same.

Describing the invention in broad terms, it will be seen that a tub A is provided and supported well above the floor by a pair of legs B. Within the tub is a tumbling barrel C which is intended to be rotated by an electric motor D through suitable gearing contained within the housing E. Beyond one end of the tub A is a secondary rinsing tub F. The tumbling barrel contains a mass G of burnishing balls in which the silver H becomes buried when the machine is in operation. The improved outlet trap is designated as J and the improved clutch slides into the supplemental housing K supported upon the main gear housing E.

Describing the invention and machine in more detail it will be seen that the main tub has vertical end walls 10 and short vertical side walls 11 which slant inwardly and downwardly as at 12 to meet the bottom of the tub 13 which bottom slants downwardly from the vertical end walls to terminate in a downwardly depending flanged opening 14 to which the trap J is attached.

The tumbling barrel C comprises a rectangular open sided center portion 15, the open sides of which are closed by the covers 16 and 17, which covers have flat tops 18 and tapered

side walls 19. Due to the shape of the covers, the tumbling barrel in end view or cross section is of an octagonal shape.

The covers 16 and 17 are provided with 5 arms 20 which are pivotally supported as at 21 upon struck-out portions 22 of the barrel main center portion 15. The covers 16 and 17 are pivotally supported at opposite edges of the barrel portion 15 with the result that 10 they open in opposite directions when swung upon their pivots.

Each cover has extending across its front edge a shaft 23 supported in ears 24 struck-up from the cover. These shafts are free to 15 revolve in their supports and have fixed to them two coil springs 25 which have one end 26 bearing against the cover, which construction causes the shaft 23 to rotate against spring tension. Fixed upon the ends of the 20 shaft beyond the barrel ends are locks or latches 27 provided with cut-out portions to form shoulders 28 adapted to engage the under side of the outwardly extending pins 29 carried by the ends of the main barrel 25 portion 15.

The latches carry outwardly extending pins 30 which form handle grasps. The latches are provided with inclined inner edges 31 with the result that when the covers 30 are forced into position, this inclined portion of the latches will ride over the pins 29 and the latches will automatically move into place under the pins due to the springs 25. To release the latches, they are pulled outwardly 35 by means of the handle grasps 30.

To insure that the covers make a water-tight closure the upper edges of the center portion 15 of the barrel carry rubber gaskets 32 while the lower edges of the covers are 40 grooved as at 33 for the reception of these gaskets.

The latches are provided with extended shoulders at their pivot ends to limit their travel so that they just unlatch and act as a 45 fixed lever against the cover for lifting it without putting any undue strain on the springs. The travel of the latches are also limited in the opposite direction so the spring tension cannot be relieved and if the cover 50 should drop, the latches will ride over the pins and hook automatically.

In the operation of the machine, the tumbling barrel is filled approximately half full of a burnishing mass G which is composed 55 of steel balls or other shaped burnishing members. Into the remaining space within the barrel the silver H is introduced. A burnishing compound and water is also placed in the tumbling barrel. When the barrel is 60 rotated, a tumbling action takes place which burnishes the silver. The length of time of the operation is dependent upon how badly the silver is tarnished. Needles are sometimes used as a part of the burnishing mass, 65 as it has been found that they will clean the

highly embossed or roughened portions of the silver better than the round balls.

The barrel is provided at one end with a stub shaft 34 which is rotatably supported in a bearing 35 at one end of the tub. At its other end the barrel is provided with an elongated shaft 36, the supporting bearing for which is the gear housing E. This shaft extends through the gear housing and through the clutch housing K and has its outer end 37 supported in the bearing 38 formed as a part of said clutch housing.

The drive motor D is supported upon a bracket 39 and is provided with a shaft D' connected to a shaft 40 by a flexible coupling 40' into the gear housing and carries a worm gear 41 which meshes with a worm wheel 42 which is free to rotate upon the shaft 36. This worm wheel 42 carries an attached clutch member 43. The clutch proper is in reality a double clutch and is indicated at 44. This clutch 44 is free to slide upon a key 45 of the shaft 36 and is operable through the medium of a yoke 46 which can be actuated by the clutch handle 47. The inner face of the clutch housing K is provided with a clutch portion 48. From the description just given and by reference to Figure 5, it will be seen that the clutch 44 can be positioned so that it does not engage either the worm clutch 43 or the housing clutch 48. When so positioned, the clutch is in its neutral position and although the motor may be running and the worm wheel 42 revolving, the shaft 36 is stationary. By moving the clutch 44 so that its 100 clutch face 49 engages the worm clutch 43, driving connection is made with the shaft 36 and the barrel is caused to rotate. By moving the clutch 44 so that its clutch face 50 engages the clutch 48 of the housing K, the shaft 36 105 and the barrel is locked against rotation.

This clutch construction is desirable as will appear hereinafter from the description given in respect to the removal of the silver from the tumbling barrel.

A rectangular basket L having sheet metal side walls is provided for use in removing the silver from the burnishing mass. The removal of the silver from the burnishing mass by hand is not only slow, but is also 115 dangerous to the hands of the operator. It has been found that in removing the silver, the tines of a fork will run beneath the finger nail of the hand of the operator and inflict a painful injury. Furthermore, the burnishing mass may include a great many different shaped burnishing members, such as sharp needles, which are also liable to both painfully and seriously injure the hands of the operator attempting to remove the silver 120 from the mass, piece by piece.

The metal basket L, however, solves the problem of removing the silver safely and quickly. This basket has a wire mesh bottom 51. At its sides the basket is provided 130

with wire handle members 52 which extend into the opposite cover member. This basket is of a size and shape to permit its insertion into the central portion 15 of the barrel after 5 one of the covers has been lifted. The depth of the basket is such, as will be seen by reference to Figure 2 of the drawings, that it extends beyond the central portion of the barrel into the remaining cover portion of the 10 barrel and has a shape corresponding to the shape thereof.

While in the drawings and specification we have shown a basket with sheet metal walls and a foraminous bottom portion, we are 15 aware that the basket could be made entirely of sheet metal and perforated or the basket could be made entirely of wire netting without departing from the spirit of our invention.

20 In using this basket it is placed in the barrel in an inverted position and to prevent its becoming wedged by reason of some of the balls of the mass getting between its side walls and the side walls of the barrel, the 25 handles 52 of the basket are so shaped that they will tend to push inwardly towards the center of the barrel any silver or burnishing members which might lie close against the inner surface of the barrel walls and thus facilitate the positioning of the basket in the 30 barrel.

After the basket has been placed in the barrel in an inverted position as indicated in Figure 2 of the drawings, the cover is lowered and locked and the barrel is given a half rotation by hand to bring uppermost the opposite cover which is then lifted. The handles of the basket can then be grasped and the basket pulled upwardly and out of the 40 barrel. The wire meshed bottom of the basket permits easy passage of the burnishing mass, but the mesh is of such a size that the silver cannot be passed through it. Thus, it will be seen that when the basket is completely removed, the burnishing mass remains 45 in the barrel while the basket will bring out all of the silver originally introduced into the machine. During the placing of the basket in the barrel, the clutch is positioned to 50 lock the barrel against rotation, otherwise the barrel might rock and allow the burnishing mass to spill into the tub. When the basket is properly positioned in the barrel and the cover locked, the clutch is moved to a neutral 55 position thus permitting a half rotation of the barrel by hand and when the barrel has been rotated to bring the opposite cover into the upper position, the clutch is again moved to lock the barrel against rocking or rotation 60 during the removal of the basket.

For the purpose of convenience, the rinsing tub F is provided, which has adjacent its upper ends shoulders 54 upon which the basket is supported. When supported in this 65 position, rinsing water can be poured on the

silver in the basket to wash from it any foreign matter.

It is impossible during the operation of the machine to prevent some of the balls and needles of the burnishing mass from falling 70 into the tub A. Likewise some of the burnishing balls and needles find their way into the rinsing tub as some of the balls and needles of the burnishing mass are found in the spoons and other silver articles removed 75 from the barrel. The tub A can be connected by a pipe 55 with the drainage system of the building in which the machine is used or a pail can be placed under the same and it is 80 desirous to prevent the passage of any of the burnishing mass into the sewage system as it may clog the same or into the pail and furthermore it is not desirable to lose any of the burnishing mass as its replacement, of course, 85 would mean an outlay of money. To meet this requirement the outlet 14 of the tub is provided with a trap J. The trap J comprises a casting 56 having a passageway 57 registering with the outlet 14 of the tub. Spaced from the central passageway 57 is 90 a supplemental outlet bend 58 into the end 59 of which is fitted the outlet pipe 55. This trap carries a removable U-shaped cover 60 having a bayonet slot connection 61 with the trap, which connection supports the cap so that its bottom 62 is in spaced relation with the lower ends of the passageways 57 and 58 thus forming a space for the reception of 95 any of the balls or other burnishing members of the burnishing mass which may fall into 100 the tub.

These balls and other shaped burnishing members remain in the cap due to their weight, while any water in the tub will pass 105 outwardly through the passage 58 into the outlet pipe 55 or into a pail.

It is intended that a trap of similar construction be provided for the rinsing tub, although it will be obvious that the trap for the rinsing tub can be done away with by providing the means for draining the rinsing 110 tub into the main tub A.

In the construction of latch as shown in Figures 9 and 10, 63 indicates a portion of the tumbling barrel, 64 the cover therefor which is adapted to engage a packing 65 forming a water-tight joint between the cover and barrel. Formed integral with the cover is a bifurcated ear 66, the walls of the bifurcations being apertured through which extends 115 a shaft 67 on which is mounted a handle lever 68 carrying a pivoted bale 69 which is adapted to engage the curved under edge of a lug 70 carried by the barrel 63 for locking the cover in position within the barrel so as to 120 clamp the cover tightly against the packing in order to form a water tight joint.

In Figure 11 we have shown a burnishing member 71, which has a spherical portion and a tapering portion extending from a 130

central circular portion having tapering walls so as to provide sharp edges to facilitate the cleaning of irregular shaped silverware, but it is, of course, understood that these 5 burnishing members can be used alone or in connection with balls, needles, or any other objects to form a burnishing mass for cleaning silver.

In the modification shown in Figures 12 10 and 13, 72 indicates a tub which is provided with an outlet trap 73 and mounted within the tub is a tumbling barrel 74 having removable covers 75 and 76, said tumbling barrel being rotated by a drive mechanism 77 constructed substantially as shown in the preferred embodiment of our invention. Arranged within the tumbling barrel formed by the central portion and covers is a foraminous lining 78, preferably formed of metal so as 15 to snugly fit the inner wall of the central portion and cover portions to form a basket for separating the silver from the burnishing members, the sides of said lining terminating in beveled portions 79 so as to force any 20 of the articles of silver or burnishing members inwardly as the basket or lining is being inserted within the barrel. The lining conforms to the shape of the barrel and has openings 80 forming hand openings so that 25 when the cover 75 is removed, fingers can be inserted through the openings 80 in order to raise the basket upwardly through the mass of silverware and burnishing articles and the burnishing compound and water. 30 The lining is preferably formed of sheet metal and has conical shaped openings formed in the lower portion thereof to prevent the prongs of forks or any other silverware being cleaned from passing between the lining and 35 the inner wall of the barrel, whereby a construction is provided which snugly fits the inner wall of the barrel in such a manner that it is impossible for any articles of the silver to become caught in the foraminous lining 40 45 when the tumbler is rotated.

This provides a construction of basket which can be inserted in the tumbling barrel through one of the cover openings and withdrawn through the other cover opening in 50 order to separate the silver from the burnishing members and with a construction of basket as herein shown, the basket can be inserted within the tumbling barrel before the mass of silver and burnishing articles are 55 placed therein and can remain within the barrel as the tumbler is being rotated for cleaning the silver. After the silverware has been cleaned, by removing the cover 75 the basket can be raised vertically so as to allow 60 the small burnishing members to pass through the openings in the basket whereby the silver will be separated from the burnishing articles and can be removed therefrom without any danger of the hands being injured. The basket containing the silverware is then placed in

a rinsing tank as will be hereinafter fully described.

After the articles have been cleaned and it is desired to clean additional articles, the articles to be cleaned are then dropped into the 70 tumbler upon the mass of burnishing articles, burnishing compound and liquid which has remained within the tumbling barrel and the basket is inverted and forced downwardly into position within the tumbling barrel and 75 the cover is inserted and clamped in position by the latches. The tumbling barrel then can be rotated with the basket within the barrel so as to thoroughly burnish and clean the articles of silverware and after they have 80 been burnished, the operation can be repeated so that the silverware is removed from the tumbling barrel and the burnishing articles will remain therein.

Arranged to one side of the tub 72 is a rinsing tank 81 provided with an outlet trap 82, said rinsing tank being herein shown detachably supported on the tub by a bottom support 83 and an outwardly extending flange 84 which has a downwardly extending edge 85 adapted to fit within the groove 86 formed in the upper edge of the tub so that the rinsing tank can be attached and detached. The rinsing tank is provided with a shoulder 86 for supporting a basket 78 in position therein, said tank having a hot water inlet pipe 87 and an overflow 88, the inlet 87 being below the normal level of water within the rinsing tank so that the water passing up through the foraminous basket containing the silverware 90 will float off the dirt and foreign matter and by moving the basket up and down through the water, the silverware will be thoroughly rinsed.

While in the drawings we have shown and described the rinsing tank detachably mounted, it, of course, could be formed integral with the tub without departing from the spirit of our invention.

In the construction as shown in Figures 12 and 13, we provide a burnishing machine with a foraminous basket forming a lining snugly fitting the inner wall of the tumbling barrel formed by the central portion and cover which conforms to the shape of the barrel and cover members so as to fit snugly against the walls thereof in order to prevent any of the burnishing articles from working between the outer faces of the basket and the inner faces of the tumbling barrel.

This provides a construction which forms a lining which increases the life of the barrel as the basket wears instead of the tumbling barrel and by this construction the basket can be inserted through either one of the 110 openings of the barrel which are closed by the cover members and the barrel can be rotated with the silverware and burnishing members 115 therein and after the silverware has been cleaned, it can be readily separated from the 120 125 130

burnishing members and withdrawn from the barrel. This facilitates the burnishing of the silverware as after the silverware has been cleaned, it can be instantly removed 5 when the barrel is stopped and as the basket is inserted through one opening at one time and through another opening at another time, the inner faces of the cover members which are not protected by the foraminous 10 lining or basket will wear equally.

While we have shown a tub and rinsing tank connected to a sewer system, it is, of course, understood that the construction of trap can be used with burnishing machines 15 which are not connected to the sewer system, as by plugging the outlet of the trap and placing a pail under the same, the cleaning compound and liquid will drain into the pail and the burnishing articles will be caught by 20 the trap, and therefore, we do not wish to limit ourselves to the particular construction shown, as we are aware that our improved construction of trap can be used for catching the burnishing members in connection with 25 various constructions of burnishing machines.

Some of the features of the machine not previously described, but to which attention should be directed are that the gear and clutch 30 housings are grease-tight which makes it possible to ship the machine ready for use and insures a perfect lubrication of the driving means for the machine. The shape of the main tub A is such as to insure complete drainage. This is quite important as from 35 time to time it is necessary to flush the barrel with water and add cleaning compound. The tapering of the silver removing basket is also important as this makes it possible to introduce the basket into the barrel easily and 40 prevents any wedging of the basket during its removal.

In the drawings and description we have shown and described the bottom of the tub provided with inclined walls sloping towards 45 the trap to insure that all of the burnishing members, such as the balls, will move freely downwardly so that they will collect in the lowest part of the tub so that they can be readily removed.

50 Attention is also directed to the fact that departures from the present machine could be made without departing from the spirit of the invention. To provide greater capacity more than one tub and barrel could be mounted in a line and driven off of the same motor. Furthermore, dividing plates might be utilized in the barrel to separate two or three different varieties of silver such as sugar bowls, creamers and the like, and thus 55 permit the burnishing of them all in the same barrel at the same time. The provision of division plates for different kinds of silver will be desirable as they could not all be burnished in a single compartment very successfully.

In the embodiment of our invention where a sheet metal basket is provided for fitting snugly within the interior of the rotary tumbling barrel, the openings or perforations of the basket are placed as close together as possible to form a foraminous surface so as to allow the burnishing members to rapidly pass through the openings when the basket is raised and shaken and while in the drawings we have shown and described a particular 70 type of opening, we are aware that various changes can be made and that these openings will form a perforated surface through which the burnishing members will readily pass when the basket is raised vertically from the tumbling barrel and which will prevent the silverware from being caught and thrown as the barrel is rotated.

75 In Figures 14 and 15 we show a wooden lining for a tumbling barrel formed of two sections, a cover section 100 and a main section 101, but of course, we do not wish to limit ourselves to the forming of this tumbling barrel of only two sections, as it can be formed 80 in the same manner as the preferred embodiment of our invention with a main section and two cover sections.

85 Arranged longitudinally within the cover section and main section of the tumbling barrel are staves 102 which are held in position by head sections 103 and 104 which are secured to the end sections of the tumbling barrel by bolts 105, the heads of which are counter-sunk. The outer sections of the staves 90 of the cover section and main section are notched as clearly shown into which the projections 106 and 107 of the end sections fit so as to hold the staves in their proper position when the cover section is removed from the main section. This provides a simple means 100 of lining the tumbling barrel by staves which are held in position by head members secured to the ends of the tumbling barrel by bolts 105 whereby the lining can be readily inserted or 110 removed.

95 In Figures 16 and 17 we show a tumbling barrel formed of a main section 108 and cover section 109 provided with a composition lining formed of rubber composition 110 free 115 from sulphur placed on a canvas backing 111 and in securing this lining to the side walls and end members of the tumbling barrel, we slit the rubber as shown at 112 so that when the head of the screw or bolt 113 is passed through the slit into the body of the barrel, it can be drawn tightly down against the canvas backing and the rubber slit will close 120 itself so as to protect the head of the bolt. This provides a novel form of forming a composition lining for a tumbling barrel which can be readily inserted or removed and one which is held in position by bolts or screws, the heads of which are protected by the rubber lining so as to prevent the silverware 130

being burnished from being injured in any way.

In Figure 18 we show a divider adapted to be used in connection with a tumbling barrel formed of three discs 114, 115, and 116 connected together by rods 117, said discs being of a shape to conform to the contour of the barrel and when in position within the barrel are held in such a position that the burnishing compartment is formed to each side of the central disc 115. This provides a construction by means of which the divider can be readily inserted or removed as the rods and discs can be forced down through the mass of burnishing members or withdrawn therefrom so as to provide a tumbling barrel with a series of compartments; it, of course, being understood that by increasing the number of discs, any number of compartments can be formed in a single tumbling barrel so as to receive silverware of different kinds to be burnished.

From the foregoing description it will be seen that we have provided a burnishing machine having many novel features and so constructed that the silverware can be readily burnished without injuring the same in any way.

While in the drawings we have shown a canvas backing for the rubber lining, we are aware that other material can be substituted therefor, such as a foraminous material which may be of wire mesh or perforated sheet metal.

While in the drawings and description we have shown certain details of construction, we are aware that various changes can be made without departing from the spirit of our invention and therefore we do not wish to limit ourselves to the exact construction of forming the various members into any particular shape, as we are aware that a tub and basket can be formed of various numbers of sides and the basket is preferably formed of such a shape as to conform to the barrel.

Having thus described our invention, what we claim and desire to secure by Letters Patent is:

1. A burnishing machine for silver or the like, comprising a rotatable barrel filled with burnishing medium, said barrel having movable covers at its opposite sides, a meshed basket of a size to snugly fit within said barrel and adapted to be placed therein in an inverted position when one of said covers is raised, and means to revolve said barrel and remove said basket from the barrel through the opening closed by the second cover.

2. A burnishing machine for silver or the like, comprising a rotatable barrel carrying a burnishing mass composed of relatively small steel balls or the like, a mesh basket adapted to be inserted into said barrel in an inverted position and pulled through the

mass, the mesh of said basket permitting the passage of the particles of the mass and preventing the passage of the silver, and said basket being larger at its lower than at its upper end to prevent the wedging of the basket in the barrel.

3. A burnishing machine comprising a receptacle, a tumbling barrel rotatably mounted therein having oppositely disposed sides closed by movable covers adapted to open in opposite directions, a foraminous basket capable of being inserted in one opening and withdrawn through the other opening, means for rotating said tumbling barrel and means for stopping the rotation of said barrel and positioning the openings of said barrel in said receptacle in vertical alignment with one another.

4. A machine for burnishing silverware with burnishing members comprising a revolvably mounted tumbling barrel having open sides, covers for closing said sides and a foraminous member adapted to be inserted through one side of said barrel and withdrawn through the other side for separating the silverware from the burnishing members in said barrel and removing only the clean silverware from within said barrel.

5. A burnishing machine comprising a tumbling barrel carrying a burnishing medium, said barrel being rotatably mounted and having oppositely disposed sides closed by removable covers, a foraminous receptacle capable of being inserted in one opening and withdrawn through the other opening, means for rotating said barrel, and means for stopping the rotation of said barrel and positioning the openings of the same in vertical alignment with one another.

6. An improved method of separating silver articles from a burnishing mass in a cleaning and burnishing machine wherein the silver articles are carried in a rotatable barrel with and polished by a mass of balls or the like, comprising placing in said barrel a foraminous member of a construction to permit the passage of the members of said mass and obstruct the passage of silver and rotating the barrel one-half of a revolution.

7. An improved method of separating silver articles from a burnishing mass in a cleaning and burnishing machine wherein silver articles are carried in a rotatable barrel with and polished by a mass of balls or the like, comprising dividing said barrel into two compartments by placing therein a foraminous member of a construction to permit the passage of the members of the mass and to prevent the passage of the silver articles, and then rotating said barrel one-half of a revolution to collect in one barrel compartment the burnishing mass and in the other compartment on said foraminous member the silver articles.

8. A burnishing machine for silver or the

like, comprising a rotatable barrel carrying a burnishing mass composed of balls or the like, a foraminous member adapted to be inserted into said barrel to divide it into two compartments, means to rotate the barrel one-half of a revolution after the insertion of said member, and said member permitting the passage of the articles of the mass into the lower barrel compartment and preventing the passage of the silver into the lower barrel compartment, for the purpose described.

9. A burnishing machine for silver or the like, comprising a rotatable barrel carrying a burnishing medium, said barrel having movable covers at its opposite sides, a foraminous basket adapted to be placed in said barrel in an inverted position when one of said covers is moved, and means to revolve said barrel and remove said basket from the barrel through the opening closed by the second cover.

10. A burnishing machine comprising a rotatable tumbling barrel carrying a burnishing mass and provided with opposite disposed openings closed by covers, and a foraminous basket adapted to be inserted through one opening and withdrawn through the other opening for separating and removing the cleaned articles from the burnishing mass.

11. A machine for burnishing silverware with burnishing members comprising a rotatably mounted tumbling barrel having open sides, covers for closing said sides, means for rotating said barrel and means for stopping the rotation of said barrel with the cover members in vertical alignment with one another, and a foraminous member adapted to be inserted through one side of said barrel and withdrawn through the other side for separating the silverware from the burnishing members in said barrel.

12. A burnishing machine comprising a rotatably mounted tumbling barrel having therein oppositely disposed sides closed by covers adapted to open in opposite directions, a foraminous basket capable of being inserted in one opening and withdrawn from the other opening, and means for rotating said tumbling barrel.

13. A burnishing machine comprising a rotatably mounted tumbling barrel having oppositely disposed sides closed by movable covers adapted to open in opposite directions, a foraminous basket capable of being inserted in one opening and withdrawn through the other opening, means for rotating said tumbling barrel, and means for stopping the rotation of said barrel and positioning the openings of said barrel in vertical alignment with one another.

In testimony whereof we hereunto affix our signatures.

MORTIMER R. ANSTICE.
CLELAND C. ROSS.
